UNITED STATES PATENT OFFICE.

LOUIS F. MURPHY, OF BOSTON, MASSACHUSETTS.

DESIGN FOR A EUCHARISTIC LAMP.

Application filed November 14, 1928. Serial No. 28,872. Term of patent 14 years.

To all whom it may concern:

Be it known that I, LOUIS F. MURPHY, a citizen of the United States, and a resident of Boston, in the county of Suffolk and State of Massachusetts, have invented a new, original, and ornamental Design for Eucharistic Lamps, of which the following is a specification, reference being had to the accompanying drawing, forming part hereof, and in which—

Fig. 1 is a front elevation and Fig. 2 is a side elevation.

I claim:

The ornamental design for a eucharistic lamp as shown.

LOUIS F. MURPHY.
